UNITED STATES PATENT OFFICE.

WILLIAM C. BARDENHEUER, OF BROOKLYN, NEW YORK, ASSIGNOR TO BOORUM & PEASE COMPANY, OF NEW YORK, N. Y., A CORPORATION OF NEW YORK.

LOCKING PLUG.

Application filed May 25, 1921. Serial No. 472,442.

To all whom it may concern:

Be it known that I, WILLIAM C. BARDENHEUER, a citizen of the United States of America, residing at 696 East 19th Street, 5 borough of Brooklyn, city and State of New York, have invented certain new and useful Improvements in Locking Plugs, of which the following is a specification.

My invention relates to a removable locking plug and particularly to a plug for closing holes for keys and the like. My device is more especially adapted to prevent unauthorized access to mechanism through a hole used for the insertion of control 10 keys, levers, etc. For the purposes of illustration I have shown my invention in the accompanying drawings as applied to the opening in the frame of a loose-leaf binder through which a key is inserted to operate 15 the screw mechanism of the binder.

Fig. 1 is a broken plan of one end of a loose-leaf binder showing my plug in position for attachment to the binder;

Fig. 2 is a similar view showing my plug 25 locked in the hole, the broken section being taken on line 2—2 Fig. 4;

Figs. 3 and 4 are end views of the binder showing the plug in the hole, unlocked and locked respectively;

Fig. 5 is a section of the plug drawn to 30 a larger scale, showing the web of the key as it appears when the plug is unlocked.

Fig. 6 is a section of the plug taken on line 2—2 of Fig. 4.

It is frequently desirable to plug an opening in a cover or wall against unauthorized access to what lies behind the cover or beyond the wall. My device is especially fitted to fill this need. It consists of a plug 35 having two parts, a cover 1 and a retaining member 6, in combination with a special key fitting the plug.

Describing the device more in detail, the 40 diameter of the cover 1 is greater than the diameter of the hole 5 so that the edge 2 of the cover completely covers the opening when the plug is in the hole. On the under 45 face of the edge 2 are one or more lugs 3 which can be fitted into the notches 4 in the margin of the hole 5.

The retaining member 6 is journalled in 50 the cover by a flange 7 turning in a groove 8 in the cover. Thus rotation is the only relative movement which the two parts can have. The body 9 of the retaining member

is the same diameter as the hole 5 and has lugs 10 projecting from it at the lower edge of its circumference. These lugs 10 are of the same size and circumferential location to each other as are the lugs 3. The cover 60 has a keyway 11 and the retaining member 65 a similar opening 12. My special key is so notched that when its web is in keyway 12, the keyway 11 of the cover is empty except in the central circular opening, and the key 65 can turn the retaining member without disturbing the cover.

In Fig. 1 I have shown the plug ready for insertion in the hole 5. The lugs 3 and 10 have been brought into register with each other and opposite the notches 4 in the hole. I make the relation of the keyways and lugs such that when the lugs are in register the keyways are out of register as shown in Fig. 3. With this arrangement the web of the 75 key holds the key in the plug as shown in Fig. 5 until the parts are rotated to the locking position shown in Fig. 4. It is impossible to lose the plug or key when out of the hole because they cannot be separated until 80 the two parts of the plug are so rotated to locking position. The key and plug can be carried around on a key ring conveniently.

When the plug is inserted in the hole 5 the lugs 10 pass through the notches 4 and 85 lie below the plate containing the hole 5. The lugs 3 engage the notches 4 and prevent rotation of the cap. By turning the key the web in the keyway 12 rotates the retaining member 6, bringing the keyways 90 into register and the lugs out of register, as shown in Fig. 4. The key can now be removed. The lugs 10 have been rotated from insertion position and underlap the margin of the hole, as shown in Figs. 2 and 6. The 95 cover and retaining member are thus each interlocked with the plate or body containing the hole.

It will be apparent, since the plug cannot be removed until the two parts are rotated in relation to each other, and the cover cannot be rotated at all, that the plug cannot be taken out except by the use of my special key.

What I claim is:—

1. A removable plug adapted to interlock with a body having a hole therein, comprising a retaining member adapted to underlap the hole and a cover adapted to conceal the retaining member and overlap the hole, 110

said members being rotatably attached together, in combination with a key adapted to pass through said cover and rotate said retaining member.

5. 2. A removable plug having two members adapted to interlock with a plate having a hole therein, comprising a retaining member adapted to underlap the hole, and a cover adapted to conceal the retaining member and 10 overlap the hole and engage with said plate to prevent rotation with relation thereto, said members being rotatably attached together; in combination with a key adapted to pass through said cover and rotate said 15 retaining member.

3. A removable plug having two members adapted to interlock with a plate having a hole therein, comprising a cover adapted to conceal the other member of the plug and 20 overlap the hole, and means on said cover adapted to prevent rotation of said cover with relation to said hole, in combination with a retaining member constituting the other member, said members being attached 25 together but rotatable with relation to each other, lugs on said retaining member adapted to underlap the edge of the hole when rotated out of inserting position; and a key adapted to pass through said cover and rotate 30 said retaining member.

4. A removable plug having two members adapted to interlock with a plate having a hole therein, comprising a cover adapted to conceal the other member of the plug and 35 having a keyway therein, and means on said cover adapted to prevent its rotation with relation to the hole, in combination with a retaining member constituting the other member and having a keyway therein and 40 adapted to underlap the edge of the hole except when in inserting position, said members being attached together and confined in relative movement to rotation; and a key adapted to rotate said retaining member, 45 the keyways in said cover and retaining

member permitting insertion and withdrawal of the key only when said retaining member underlaps the edge of the hole.

5. A removable plug having two members adapted to interlock with a plate having a notched hole therein, comprising a cover adapted to conceal the other member of the plug and having a keyway therein, a retaining member constituting the other member and having a keyway therein, said members being attached together and freely rotatable with relation to each other, lugs in said cover adapted to fit the notches in the hole and prevent rotation of said cover, and lugs on said retaining member adapted to pass 60 through said notches when in register with the cover lugs and to underlap the edge of the hole when out of register therewith, in combination with a key to turn said retaining member. 65

6. A removable plug having two members adapted to interlock with a plate having a notched hole therein, comprising a cover adapted to conceal the other member of the plug and having a keyway therein, a retaining member constituting the other member and having a keyway therein, said members being attached together and freely rotatable with relation to each other, lugs in said cover adapted to fit the notches in the 70 hole and prevent rotation of said cover, and lugs on said retaining member adapted to pass through said notches when in register with the cover lugs and to underlap the edge of the hole when out of register therewith, in combination with a key to turn said retaining member; the keyways in said cover and retaining member being positioned to permit withdrawal of said key only when said lugs are out of register with each 75 other. 80

In testimony whereof I have signed my name to this specification.

WM. C. BARDENHEUER.
